TRIGGER FOR A GEAR SHIFT STICK

George H. Hurst, Jr., Abington, Pa.
(341 W. Glenside Ave., Glenside, Pa.)

Filed Oct. 22, 1964, Ser. No. 82,279

Term of patent 14 years

(Cl. D14—6)

Fig. 2.

Fig. 4.

Fig. 1.

Fig. 5.

Fig. 3.

FIG. 1 is a side elevational view of a Trigger for a Gear Shift Stick embodying my new design,
FIG. 2 is a top plan view of the same,
FIG. 3 is a bottom plan view of the same,
FIG. 4 is left hand elevational view of FIG. 1,
FIG. 5 is a right hand elevational view of FIG. 1.
The fragmentary gear shift stick shown in broken lines in FIG. 1 is included for illustrative purposes only.

I claim:

The ornamental design for a trigger for a gear shift stick, as shown and described.
